DOORSTOP

Charles H. Martin, Los Angeles, Calif.

Application March 20, 1946, Serial No. 655,706

3 Claims. (Cl. 16—86)

1

This invention relates to door stops and has for its primary object to provide one which is effective in use but which can readily be bent or flexed in any direction by floor cleaning instruments for cleaning access to floor areas beneath the stop.

Another object of the invention is to provide a door stop which can be flexed in any desired direction and to any desired degree without danger of overstressing the means permitting the flexing thereof.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a broken plan view showing the door stop in applied position, the door stop being partly in section.

Fig. 2 is an end view of the door stop.

The door stop 5 of the present embodiment is shown applied on a base board B in a position to intercept a door D and to prevent the hardware of the latter from marring the surface of the wall W.

The door stop 5 comprises, generally, a base or escutcheon plate 6, a stem 7 centered thereon and extending transversely outward, means 8 connecting the plate and stem and including compressible means 9 whereby said stem may be displaced with respect to its normal position but will return to its normal position upon release, and a bumper tip 10 on the outer end of the stem.

The escutcheon plate which is illustrated is of generally oval form and is adapted to be permanently secured to a wall or the base board B thereof by screws 11 either above and below or on either side of the stem 7. In its preferred form, an ear 12 is sheared and struck at right angles from the plate 6, said ear being provided with an eye 13.

The stem 7 simply comprises a thin walled tube of suitable length with one end provided with an inwardly directed annular flange 14. The bumper tip 10 which is made of soft rubber or like ma-

terial is insertable into the other end of the stem 7 as by means of its reduced cylindrical portion 15 so that its suitably domed head 16 may serve to engage the door D to receive the shocks transmitted thereby.

The means 8 comprises a rod 17 having at one end a hook 18 engaged in the eye 13 and arranged longitudinally in the stem 7. The other end of the rod 17 may be threadedly or permanently connected to a plate or abutment washer 19 slidably movable in the stem. When a threaded connection is used, the effective length of the rod may be varied.

The compressible means 9 comprises a coiled compression spring confined between the flange 14 of the stem and the mentioned abutment washer 19. Said spring can be variably loaded by adjusting the abutment washer 19 along the rod 17.

The door stop above provided fully realizes the objects and purposes of the invention in a simple and effective manner. It will be noted that the spring 9, by reactive pressure, urges the flanged end of the stem 7 flat against the escutcheon plate 6 and, therefore, holds said stem in door shock receiving position outwardly at right angles to said escutcheon plate. However, a broom, mop, carpet sweeper, or vacuum cleaner will readily angularly displace or move the stem by a commensurate compression of the spring 9 as the displacement occurs. Inasmuch as the spring cannot be over tensioned, it retains its effectiveness under all conditions and cannot lose its tension even under exaggerated displacement of the stem.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a door stop, a base plate for attachment to a baseboard and having an integral ear formed and extending outwardly from and at right angles to said plate provided with an eye, a rod having a hook on one end engaged in said eye, an abutment plate on the rod, a tubular stem engaged over the rod and having an inwardly directed flange and a central opening, and compressible means engaged with the abutment plate and the stem for normally holding the latter at right angles to the base plate.

2. In a door stop, a base plate adapted to be secured to a baseboard, said plate having struck therefrom an ear extending at right angles to said plate, a tubular body having an inwardly directed flange at right angles thereto and central opening, said ear extending into said opening and having an aperture, a rod within said tubular body having at one end a hook engaged in the aperture of said ear, and at the other end free end an abutment plate adjustable thereon, and a spring between said inwardly directed flange of said tubular body and said abutment plate for holding the tubular body at right angles to the base plate.

3. In a door stop, a plate for attachment to a baseboard, said plate having an ear struck therefrom and bent at a right angle to said plate and said ear having an aperture, a tubular body having an inwardly directed flange at the bottom normally parallel to said plate, said apertured ear extending into said tubular body, centrally of the 20

flange thereof, a rod in said body having one end pivotally engaged in the aperture of said ear, and provided with threads at the other end, an abutment plate engaging the threads of said rod for adjustment thereon, and a spring surrounding said rod and disposed between said abutment plate and the flange of said tubular body to maintain said tubular body normally at right angles to said base plate.
